MODULATOR

Frederick E. Terman, Stanford University, Calif.

Application March 9, 1936, Serial No. 67,866

7 Claims. (Cl. 179—171)

My invention relates to modulators, and more particularly to thermionic modulator tubes which operate in conjunction with high frequency generators or amplifiers by varying radio-frequency losses at the modulation frequency.

Among the objects of my invention are: To provide a simple and easily controlled loss modulation system; to provide a simple modulation system which can be readily applied to existing code transmitters; and to provide an improved type of loss modulator in which the degree of modulation obtainable, the linearity of modulation and the overall efficiency is greater than heretofore obtained in loss modulation systems.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

Referring to the drawing:

Figure 1 is a circuit diagram reduced to lowest terms, showing the modulator of my invention applied to a power amplifier output.

Figure 2 is a circuit diagram where the method is applied to the modulation of an oscillator output.

Figure 3 is a circuit diagram showing how the modulator of my invention may be applied to a high frequency transmission line.

Figure 4 is a graph illustrating certain tube characteristics.

Referring directly to Figure 1 for a more detailed description of the various applications of my invention, a power amplifier tube 1, preferably of the thermionic type, is connected to a source, such as a master oscillator, through input leads 2—2, one of which, as is well known, leads to the cathode of the tube, the other leading to the grid 3. The anode 4 of the tube is energized through a radio-frequency choke 5, and a constant-current choke 6 from a source 7. The choke 6 is proportioned so that the current which flows through it is substantially constant insofar as any tendency toward variation at the modulation frequency is concerned.

In the particular circuit shown in Figure 1 the output of the power amplifier tube 1 is led through a blocking condenser 8 to a tank cir-

cuit comprising inductance 9 and condenser 10, this tank circuit having coupled to the inductance 9 thereof an output coil 11, the ends of which may be connected to any convenient radiator.

A losser tube 12, of a convenient size and of the fundamental three-electrode type, is connected directly across the tank circuit 9—10, with the losser tube anode 14 connected to one side thereof and the losser tube cathode 15 connected to the other side.

The losser tube grid 16 is connected to the losser tube cathode through a transformer secondary 17 and a bias source 18. Modulation frequency is applied from input leads 19 to a primary 20, coupled to secondary 17.

In Figure 2 somewhat the same arrangement is shown except that the losser tube 12, with its associated input circuits, is connected across the tank circuit of a conventionalized oscillator tube 21, with its associated coupling circuit 22 arranged to cause the tube 21 to self-oscillate. Power is taken from the oscillator circuit 22 in the usual manner through coupled coil 11. In this case the oscillator tube is energized through a constant-current choke 6, the oscillator tube 21 being parallel fed, the oscillator circuit being isolated from the anode potential by blocking condenser 8.

It will be seen by inspection of Figures 1 and 2 that the losser tube shunts across the tank circuit a resistance which can be varied by the modulating voltage acting on the grid 16 of the losser tube 12. This causes a radio-frequency current, which the plate circuit of the losser tube draws, to vary with the modulating voltage.

The operation of my modulating system is as follows: The grid bias of the losser tube 12 is normally adjusted so that when no modulating voltage is applied a part of the radio-frequency output appearing in the tank circuit is absorbed by the losser tube 12. The tank circuit power not absorbed by the losser tube then represents the carrier output. If one hundred per cent modulation is to be provided for, one-half of the total tank circuit power must be absorbed in the losser tube, while the remaining half represents the carrier. If the maximum degree of modulation desired is less than one hundred per cent, a larger proportion of the total power is available as the carrier.

Upon application of a modulating voltage to the grid of the losser, the resistance shunted across the tank circuit of the power amplifier 55

(or oscillator) tube is alternately increased and decreased in accordance with the modulation. Now in an ordinary power amplifier or power oscillator, the tendency is for the amplitude of the voltage developed across the tank circuit to remain constant as the load on the circuit varies, while the d.-c. plate current tends to vary with the load. Thus, in an ordinary circuit the lower the resistance of the losser tube, the greater would be the d.-c. plate current; while the more the resistance, the smaller would be the d.-c. plate current. The amplitude of oscillations would then tend to vary only slightly even with large changes in the resistance of the losser. It is for this reason that previous types of loss modulators have not been very satisfactory.

This difficulty is overcome in Figures 1 and 2 by the addition of the constant-current choke 6, which keeps the plate current from varying at the modulation frequency. The result is that as the losser resistance shunted across the output tank circuit in Figures 1 and 2 varies, the voltage across this circuit must also vary, since the d.-c. plate current remains fixed. Thus, if the resistance across the tank circuit is lowered considerably, the instantaneous effect is to absorb energy from the tank circuit and to produce thereby a slight reduction in the tank circuit voltage. In an ordinary power amplifier or oscillator this slight decrease in voltage would cause sufficient increase in d.-c. plate current to supply the large additional losses. However, the presence of the constant current choke 6 in Figures 1 and 2 prevents the increase in plate current, so that the amplitude of oscillations decreases further until the voltage across the tank circuit has dropped to the point where the energy in the tank circuit is small enough to be sustained with the original d.-c. plate current.

If the resistance which the loss tube shunts across the tank circuit is increased, the reverse situation exists. The first effect of such a reduction of losses is to increase the amplitude of oscillations slightly, and if it were not for the constant current choke the d.-c. plate current would then drop. However, since the plate current cannot drop, the tank circuit receives excess energy that increases the amplitude of oscillations until an equilibrium is established between the output power and the d.-c. input power at the constant current.

It will be noted that the use of the constant current choke increases greatly the degree of modulation obtained with a given variation in loss, and also increases considerably the linearity of modulation.

One of the principal merits of the constant-current system of loss modulation, as contrasted with previous loss modulators, is in the improved overall efficiency which is obtained. It will be noted that when the resistance of the losser tube is increased, the voltage applied to the plate of the power tube is increased, since in attempting to maintain constant current, the choke 6 has induced across it a voltage that adds to the supply voltage. Likewise, when the resistance supplied by the losser tube decreases, the voltage at the plate of the power tube is likewise decreased, since the constant-current choke, in attempting to prevent the current through it from increasing as a result of the greater load placed on the tank circuit, has induced across it a voltage that subtracts from the plate supply voltage. Hence, during the positive half of the modulation cycle the plate voltage is large and the power input to the

tube is likewise large, while during the negative half of the modulation cycle the plate voltage is low, and the power input to the tube is correspondingly small. The battery, however, supplies constant power at all times. The meaning of this is that the choke stores energy during the parts of the modulation cycle when the amplitude of the wave envelope is low, and then delivers this energy to the tube during the parts of the modulation cycle when the amplitude of the wave envelope is great. This action of the choke helps out the losser tube and reduces the work which it must do.

A numerical example will make the power relations somewhat clearer. It will be assumed that the plate efficiency of the power tube is constant throughout the modulation cycle. This is not strictly true but will be used in the example because it simplifies the explanation greatly. It will be assumed that a carrier power of 300 watts is desired, that the degree of modulation to be obtained is seventy-five per cent, and that the plate supply voltage is 2,000 volts. When no modulation is applied the losser tube must absorb an amount of power equal to the degree of modulation times the carrier power, which is $300 \times 0.75 = 225$ watts. The power tube is, therefore, called upon to generate $300 + 225 = 525$ watts of radio frequency power at a plate supply potential of 2,000 volts. This determines the size of power tube. When modulation is applied, the total radio-frequency power at the crest of the modulation cycle is, where m = the modulation expressed as a decimal $300(1+m)^2 = 918$ watts for seventy-five per cent modulation. As the losser will be adjusted so that it absorbs little or no power at the crest of the modulation cycle, the 918 watts represents the total peak power generated by the power amplifier or oscillator tube. It will be observed that of the 618 watts difference between the peak power and carrier power, 225 watts were released by reducing the losser absorption to zero while the remaining 393 watts are supplied from the constant-current choke. At the trough of the modulation cycle the total output power required is, where m = the modulation expressed as a decimal 300

$$(1-m)^2 = 18.75$$

watts for seventy-five per cent modulation. The amplitude of oscillations is now one-fourth of the carrier amplitude, and the total radio frequency power generated is also one-fourth of the total power with no modulation, or

$$525/4 = 131.25$$

watts. This is because at one-fourth amplitude the plate voltage has dropped to one-fourth normal, but the plate current is held constant by choke 6. The difference of 112.5 watts between this 131.25 watts and the required output of 18.75 watts, represents the energy which the losser tube must absorb.

These results show that in order to obtain 300 watts carrier power, modulated seventy-five per cent with the constant-current loss system of modulation, the power amplifier or power oscillator must be capable of developing a radio-frequency output of 525 watts, while a losser tube must be provided that is capable of dissipating 225 watts. The total plate loss rating of the losser tube plus the power tube, assuming the latter operates at sixty-seven per cent efficiency, is 487 watts. In the case of a conventional plate-modulated power amplifier (or oscilla-

5 tor) using a class A modulator system, the total dissipation would be approximately 600 watts for power tube and modulator taken together, while if class B modulation were employed the total 10 plate dissipation which must be provided is of the order of 270 watts. From the point of overall plate efficiency it is, therefore, apparent that the loss system of modulation herein described stands between the class A and class B modulation 15 systems.

10 It is to be noted that the losses in the losser tube are maximum when the wave is unmodulated, and decrease as the modulation is applied. This results from the fact that the source of plate 15 voltage supplies the same current and hence the same power irrespective of the presence or absence of modulation, but since the modulated wave contains more energy than the unmodulated wave, the losser tube obviously absorbs less energy during modulation. This result is clearly 20 brought out from the example considered above, as it will be noted that the losser tube absorbs no energy at the peak of modulation and absorbs only half as much energy at the trough of modulation as when no modulation is present.

25 One of the distinguishing features of the constant-current loss modulator is the ease with which it can be applied to a transmitter. The losser tube can be connected anywhere in the circuit, as for example across the radio-frequency transmission line, across the tank circuit, or across a tuned circuit coupled to the transmission line (see Fig. 3). In order to apply the modulation system to a code transmitter it is merely 30 necessary to add the constant-current choke to the plate-supply system of the power tube, and to couple in the losser at some accessible point. In particular, it will be noted that the losser may even be an external unit separate from the 35 transmitter mounting.

40 In Figure 5 I have shown the losser tube inserted across a transmission line 25, this transmission line being fed from any convenient circuit 26 carrying radio-frequency power. In this case 45 I prefer to couple the anode circuit of the losser tube 12 to the transmission line through a transformer 27. In this figure I have not shown the insertion of the constant-current choke in the plate supply system of the power tube, inasmuch as this power tube and circuit therefor may be 50 any one of a large number of kinds.

55 For best results the losser tube should be operated in such a way that a high radio-frequency voltage is applied to its plate. The losser tube should also have characteristics such that the losses increase very rapidly when the instantaneous plate voltage is greater than the plate voltage at which current begins to flow to the 60 losser plate. Such a characteristic is indicated by the solid lines 30 in Figure 4, whereas the dotted lines 31 represent an undesirable characteristic. It will be noted that what is desired is 65 essentially a high mutual conductance. Tubes with low amplification factor are therefore in general to be preferred.

70 The bias on the losser tube is so adjusted in operation that when no modulation is applied the losses have the proper value to provide for the degree of modulation desired. With this adjustment, together with a tube having a steep characteristic such as shown by the solid lines of Figure 4, any variation in grid potential produced by the modulating voltage will tend to cause the amplitude of oscillations to vary almost exactly 75 with the variation in grid bias. This is because

the plate potential at which plate current starts to flow in the losser is proportional to the grid bias, and if the losses in the tube increase very rapidly as the plate potential exceeds the cut-off value, then the amplitude of oscillations will always be such as to drive the plate of the losser tube just slightly beyond the point at which plate current starts to flow. Such a condition assures that the modulation will follow the modulating voltage and hence be substantially distortionless. 10

15 It will be noted that the essential feature of the modulator herein described is the operation with constant d.-c. plate current, and that the desirable results which are obtained are a consequence of the cooperation of the constant-current 15 choke and the losser system. It is this feature that distinguishes my new type modulator from previous loss modulators.

I claim:

1. In combination with an electron discharge 20 device having a circuit to which oscillating power is supplied by said device, means for modulating said power which comprises an absorber modulator connected across at least a portion of said circuit to which oscillating power is supplied, 25 means for supplying a modulating frequency to said absorber modulator, and means for maintaining the direct anode current of said electron discharge device constant.

2. In combination with an electron discharge 30 device having a circuit to which oscillating power is supplied by said device, means for modulating said power which comprises an absorber modulator tube having a cathode, anode, and control electrode, said anode and cathode being connected across at least a portion of said circuit to which oscillating power is supplied, means for supplying a modulating frequency to the control electrode of said absorber modulator tube, and a choke in the direct current anode supply circuit of said electron discharge device to maintain a constant current therein. 40

3. In combination with an oscillator having an electron discharge device and a circuit to which oscillating power is supplied by said device, means 45 for modulating said power which comprises an absorber modulator tube having a cathode, anode, and control electrode, said anode and cathode being connected across at least a portion of said circuit to which oscillating power is supplied, means for supplying modulating frequency to the control electrode of said absorber modulator tube, means for altering the magnitude of said oscillating power in accordance with the charge on said absorber modulator tube control electrode, and means for maintaining the direct anode current constant on the electron discharge device of said oscillator. 50

4. The method of modulating the high frequency output of an electron discharge oscillator 60 which comprises maintaining a constant direct anode current to said oscillator, absorbing a variable amount of power from said high frequency output only, and reducing the instantaneous potential across said absorbing means in proportion to the modulation energy. 65

5. In combination with an electron discharge device and a circuit in which oscillating power is controlled by said electron discharge device, means for modulating said power which comprises an absorber modulator tube and circuit 70 connected to said oscillating power circuit for enabling absorption of oscillating power by said modulating means, means for supplying modulating frequency to said absorber modulator tube 75

for controlling such absorption of oscillating power, and means for maintaining the direct anode current to said electron discharge device substantially constant.

6. In combination with an electron discharge device and a circuit in which oscillating power is controlled by said electron discharge device, means for modulating said power which comprises an absorber modulator connected to said oscillating power circuit at points differing in instantaneous potential for enabling absorption of oscillating power by said absorber modulator, means for supplying modulating frequency to said absorber modulator for controlling such absorption of oscillating power, and a choke in the direct current anode supply circuit of said power

electron discharge device to maintain a constant anode current therein.

7. In combination with a power tube having a circuit to which oscillating power is supplied by said tube, means for modulating said power which comprises an absorber modulator tube having a cathode, anode, and control electrode, said anode and cathode being effectively connected to said circuit at points differing in instantaneous potential for enabling absorption of oscillating power by said absorber modulator tube, means for supplying modulating frequency to the control electrode of said absorber modulator tube for controlling such absorption of oscillating power, and means for maintaining the direct anode current constant on said power tube.

FREDERICK E. TERMAN.
